UNITED STATES PATENT OFFICE.

JOHN D. PRICE, OF CLEVELAND, OHIO, ASSIGNOR TO DRAKE PROCESS, INCORPORATED, OF WILMINGTON, DELAWARE, A CORPORATION OF DELAWARE.

SHOE AND METHOD OF MAKING.

Application filed February 25, 1922. Serial No. 539,130.

To all whom it may concern:

Be it known that I, JOHN D. PRICE, a citizen of the United States, residing at Cleveland, in the county of Cuyahoga and State 5 of Ohio, have invented certain new and useful Improvements in Shoes and Methods of Making, of which the following is a specification, reference being had therein to the accompanying drawing.

10 This invention relates to boots, shoes and like footwear and has for an object to provide an improved method of making or manufacturing such boot or shoe and an improved boot or shoe resulting from the practice of such method.

A further object of the invention is to provide in a boot or shoe an insole of such nature that parts of the same may be clinched over retaining parts whereby the 20 upper and welt may be retained in union with the edge of the insole without stitching, nailing, cementing or the like.

A further object of the invention is to provide in a shoe structure an insole having 25 about its edge a crease or groove into which the edge of the upper and the edge of the welt are inserted and bound by a wire, shackle or keeper and a part of the insole bent or clinched down over the united parts 30 to retain them in such united position.

A further object of the invention is to provide in a boot or shoe an insole of such material and construction that nails or similar penetrating implements may have their 35 heads embedded in the material of the insole with the points or penetrating ends extending therefrom over and upon which the outer sole, the heel and parts of the counter and quarters are impaled by forcing the parts on 40 to the said nails or penetrating members.

A further object of the invention is to provide an insole of such material that it may be molded into the form to conform 45 to the shape of the bottom of the foot as to convexity, concavity and arch supporting and to retain such shape or form to be unaffected by climatic conditions.

A further object of the invention is to provide an insole preferably of metal, such 50 for instance as aluminum, which will be molded or cast or otherwise bent with the necessary contours, depressions, concavities, convexities to conform to and support the entire bottom of the foot and by reason of 55 not being affected by moisture or the like

to retain such form or shape throughout the entire life of the boot or shoe whereby the foot is wholly supported and troubles resulting from unsupported parts of the feet avoided.

With these and other objects in view, the invention comprises certain novel parts, units, elements, combinations and constructions as disclosed in the drawings together with mechanical equivalents thereof as will be hereinafter more fully described and claimed.

In the drawings:

Figure 1 is a sectional view taken upon a normal vertical plane longitudinally through the major axis of a shoe embodying the present invention.

Figure 2 is an inverted plan view of the insole with the counter applied thereto but with the outer sole and heel omitted.

Figure 3 is a transverse sectional view through the shoe substantially upon line 3—3 of Figures 1 and 2 but before the connection of the upper and insole has been completed.

Figure 4 is a transverse sectional view through the heel taken on line 4—4 of Figures 1 and 2 with the counter and quarters in position upon the nails embedded in the insole but with the heel and outer sole omitted.

Figure 5 is an enlarged detail view of an edge of the insole showing the initial relation of the insole, the upper, the welt and the shackle.

Figure 6 is an enlarged detail view of the edge of a completed sole showing the upper, the welt and shackle clinched into the material of the insole and the outer sole applied to the welt by the usual and ordinary stitching.

Like characters of reference indicate corresponding parts throughout the several views.

The present invention contemplates the use of an insole 10 of some material, such as metal or the like, which will provide the required facilities to be hereinafter explained. While at present it is contemplated to employ metal for this purpose and comparatively rigid and unyielding, it is to be understood that the present invention is in no way limited to an insole of this material and any material which shall comply with the requirements of such insole is within 100 105 110

the scope of the present invention. The rigidity of the insole contemplated provides for the required or desired arch 11 with a concavity 12 at the heel and a convexity 13 at the ball of the foot, or as required. Being composed of metal or relatively unyielding material, these initial conformations are retained so that the foot, initially fitted by such a shoe, will be supported at all points throughout the life of such shoe.

In the making of the insole, a lip 14 is formed about adjacent to, but spaced from the edge of the insole as indicated more particularly at Figures 2, 5 and 6, forming a groove 15, as shown at Figures 5 and 6. Into this groove 15 the margin of the upper 16 is inserted, also the margin of the welt 17. Preferably, the margin of the welt 17 is skived to form a thinner portion at the edge which is engaged by a shackle 18 bearing upon the skived edge of the welt, the margin of the upper and, of course, any interposed sheet as the lining 19. This shackle may be of any material, preferably, though not necessarily, of wire but a cord or other attenuated member would serve the purpose relatively well. When the parts have been assembled thus in the manner shown at Figure 5, the lip 14 is bent outwardly and downwardly to the position shown at Figure 6 and by reason of its relative unyielding condition clinches or clamps the margin of the upper and the edge of the welt 17 about the shackle 18, holding all of these parts in such secured relation.

The insole is also preferably provided with nails or the like penetrating members 20 by casting or molding the heads of such nails into the material of the sole with the penetrating shanks extending in parallelism from that surface of the insole which would be the bottom of the shoe. The counter 21, properly perforated or unperforated as occasion may make desirable, is impaled upon the extended ends 20 by inverting the insole 10 upon a last or the like, the quarters 22 forming in fact a part of the upper being also and at the same time impaled upon these points so that the counter is engaged by the embedded nails, the insole being preferably provided with an ogee 23 for the receipt of the edge of the upper and counter

as indicated more particularly at Figures 1 and 4.

With the shoe still inverted, the outer sole 24 is now impaled upon the nails 20, likewise the several laminations of the heel 25.

The outer sole is now stitched about its edge by the stitching 26 to the welt 17 in the usual well known manner.

By this construction, the welt 17 is permanently fixed to the insole together with the upper making it possible to remove and replace the outer sole 24 and heels 25 as often as wear shall make necessary or desirable. While the heel 25 has been shown built up of laminations, it is obvious that molded heels of resilient material may be used, or that such heel may be integral with the outer sole 24 which may also be of such composite material as distinguished from leather, the material ordinarily entering into such parts of foot wear.

What I claim is:

1. A shoe comprising a relatively non-yielding insole conformed to the sole of a foot and of material adapted to retain its conformation irrespective of climatic conditions, and continuous unitary means extending about said sole clamping the margin of the upper about the periphery thereof.

2. A shoe comprising an insole of relatively non-yielding material initially conformed to support all parts of the foot and having a peripheral rabbet, an upper having its marginal edge seated within the rabbet, a shackle bearing upon the marginal edge of the upper, and an integral part of said insole clamped over and binding the margin of the upper and the shackle.

3. A shoe comprising a relatively non-yielding insole initially contoured to conform to and to support the bottom of a foot and to resist climatic conditions, said insole being provided with a peripheral rabbet and clinching tongue, an upper having a margin within the rabbet, a welt having a margin within the rabbet, a shackle located within the rabbet bearing upon the margins of the welt and upper and retained by the clinching of the tongue, and an outer sole stitched to the margin of the welt.

In testimony whereof I hereunto affix my signature.

JOHN D. PRICE.
